UNITED STATES PATENT OFFICE.

WILLIAM M. BRISTOL, OF HIGHLAND, CALIFORNIA, ASSIGNOR TO CALIFORNIA FRUIT GROWERS EXCHANGE, OF LOS ANGELES, CALIFORNIA, A CORPORATION OF CALIFORNIA.

DESIGN FOR A FRUIT-JUICE EXTRACTOR OR SIMILAR ARTICLE.

Application filed August 19, 1925. Serial No. 14,510. Term of patent 14 years.

To all whom it may concern:

Be it known that I, WILLIAM M. BRISTOL, a citizen of the United States, residing at Highland, in the county of San Bernardino and State of California, have invented a new, original, and ornamental Design for Fruit-Juice Extractor or Similar Article, of which the following is a specification, reference being had to the accompanying drawing, forming part thereof.

Fig. 1 is a plan view of the fruit juice extractor showing my new design, and Fig. 2 is a side elevation of the same.

I claim:

The ornamental design for a fruit juice extractor or similar article, substantially as shown.

WILLIAM M. BRISTOL.
